UNITED STATES PATENT OFFICE.

ALBERT P. FULMER AND FRANK M. NEBINGER, OF WILMINGTON, DELAWARE.

BOTTLE-CLOSURE.

1,109,570.

Specification of Letters Patent.

Patented Sept. 1, 1914.

Application filed April 2, 1912. Serial No. 688,103.

To all whom it may concern:

Be it known that we, ALBERT P. FULMER and FRANK M. NEBINGER, citizens of the United States, residing at Wilmington, in the county of New Castle and State of Delaware, have invented new and useful Improvements in Bottle-Closures, of which the following is a specification.

This invention relates to bottle closures and has for an object to provide a closure which will be particularly designed for use upon beer or like beverage bottles wherein means are employed for effectually permitting the stopper to be opened or closed.

Another object of the invention is to provide a bottle closure wherein the closure supporting bail is provided with combined guard and manipulating portions which are disposed below the plane of the eyes of the stopper lock and associated with relation to the fulcrum of the stopper lock whereby they can be readily manipulated to release the stopper from a closed position without necessitating manipulation of the stopper lock.

A still further object of the invention is to provide means for preventing the manipulating portions of the stopper supporting bail from becoming accidentally disconnected from the eyes of the stopper locking member.

In the drawing forming a portion of this application and in which like letters of reference indicate similar parts in the several views:—Figure 1 is a side view of the bottle showing the application of the stopper thereto, the stopper adjusting means of the bottle being shown in front elevation. Fig. 2 is a view similar to Fig. 1 showing the bottle adjusting means in end elevation. Fig. 3 is a view of a portion of the bottle showing the adjusting means in a position to release or open the stopper.

The bottle 1 herein shown may be of any suitable well known type, being preferably provided with a mouth or neck 2 such as is commonly employed upon beer or like beverage bottles. A bail like fulcrum member 3 embraces the neck of the bottle at a suitable point in its length, and preferably the bail is constructed of wire and provided with intertwined securing terminals 4 and fulcrum eyes 5, the latter being disposed at one side of the axial line of the bottle so that the requisite adjustment of the stopper can be effected as will be understood.

The stopper 6 may be constructed of porcelain or any other suitable material which may be best suited for the purpose, and as illustrated the said stopper is provided with a convex bottom 7 which is covered with a suitable gasket or elastic element 8 which is adapted to yieldingly fit against the walls of the mouth of the bottle when the closure is in a closed position. The adjusting member of the stopper is preferably constructed of a single length of suitable wire which is bent to form a portion 9 which extends through the horizontal aperture 10 in the stopper and to which the oppositely disposed bowed side arms 11 are connected. These side arms extend down against the sides of the neck of the bottle and at 12 the arms are offset downwardly and inwardly in the direction of the neck where they are mounted in the eyes 13 of the locking member 14. From the offset portions the arms are extended down against the sides of the neck as at 15 to form depending side arms, and said latter mentioned arms being thence bent upwardly and outwardly to opposite sides of the outer side faces of said arms to provide relatively broad manipulating portions 16. The portions 16 are preferably formed by bending or twisting the portions 16 sufficiently to permit the said portions 16 to serve as guards to positively prevent the accidental displacement of the offset portions 12 from the eyes 13 of said adjusting member. The adjusting member 14 is of the usual well known construction, being preferably constructed of a single length of wire and formed to provide branches 17 whose trunnion like portions 18 are extended into the eyes 5 as shown. From the eyes 13 of the adjusting member the wire is extended outwardly as at 19 and then curved as at 20 to present the usual locking bail.

From the construction of the device described, and incident to the fact that the eyes 13 of the locking member are disposed substantially in axial alinement with the bottle and laterally or slightly to one side of the fulcrum ends of the locking bail 19 it is evident that when the stopper is in a closed position as illustrated in Figs. 1 and 2 of the drawings the arms 11 of the stopper supporting and adjusting member will be vertically disposed. Now, it will be appreciated that the manipulating portions 16 may be pressed outwardly by the hand of the operator and placed in positions remote

from the fulcrum portions of the locking member 19 and with a resultant adjustment of the stopper to an opened position as shown in Fig. 3.

5 We claim:

The combination with a bottle having a neck and a stopper therefor, a bail encircling the neck and having its ends twisted around each other to rigidly secure the bail on the 10 neck, a plurality of opposed eyes formed on the bail, a U-shaped member having its medial portion passing through the stopper of the bottle and its ends depending adjacent the sides of the bottle, said ends being 15 adapted to bear against the sides of the bottle and offset in opposite directions at their extremities to provide bearing portions against which the fingers of the operator are adapted to press, an adjusting member 20 having its ends journaled in the eyes of the bail, eyes formed on the adjusting member and having the sides of the stopper-engaging member passing loosely therethrough,

with the said sides offset at the points of 25 passing through the eyes of the adjusting member, the said adjusting member being adapted to have its medial portion normally abut against the wall of the bottle when the stopper-engaging member is in a vertical 30 position to hold the stopper in closed position on the bottle and whereby, when pressure is exerted on the bearing surfaces of the free ends of the sides of the stopper-engaging member, the said adjusting member will have its medial portion swung out 35 of engagement with the sides of the bottle to raise the stopper-engaging member and remove the stopper from closed position on the said bottle.

In testimony whereof we affix our signatures in presence of two witnesses.

ALBERT P. FULMER.
FRANK M. NEBINGER.
